UNITED STATES PATENT OFFICE.

FRANCIS I. DU PONT, OF WILMINGTON, DELAWARE, ASSIGNOR TO BALL GRAIN EXPLOSIVES COMPANY, OF WILMINGTON, DELAWARE, A CORPORATION OF DELAWARE.

PROCESS OF PREPARING EXPLOSIVE CHARGES FOR SHELLS.

1,308,347.

Specification of Letters Patent.

Patented July 1, 1919.

Original application filed May 2, 1916, Serial No. 94,947. Divided and this application filed March 8, 1918. Serial No. 221,310.

To all whom it may concern:

Be it known that I, FRANCIS I. DU PONT, a citizen of the United States, residing at Wilmington, in the county of New Castle 5 and State of Delaware, have invented a new and useful Improvement in Processes of Preparing Explosive Charges for Shells, of which the following is a full, clear, and exact description, reference being had to the 10 accompanying drawings, which form a part of this specification.

This application is a division of an application filed by me May 2, 1916, Serial No. 94,947.

15 The connection between the time fuse of a shrapnel shell and the bursting charge is generally a series of short cylinders of compressed black powder. Each of these cylinders has a hole extending axially there- 20 through. The object of this arrangement is to produce the quickest possible transmission of fire from the time fuse in the head of the shell to the bursting charge in the base. The theory of operation of the device 25 is that the hole remaining open, the flame will instantly pass through the column of pellets and fire the bursting charge without variation in time of bursting being produced by the fire having to penetrate through a 30 column of powder which may have become packed tight by its own inertia when the shrapnel shell is started in motion in the gun.

The practical way in which this works out 35 is that there being eight cylinders or "pellets" (as they are called) and these being necessarily a somewhat loose fit in the central tube of the shell, it is nearly impossible to avoid having the cylinders nearest the 40 bursting charge crushed, in the act of firing the shell from the gun, by the accelerating force acting against the inertia of the pellets ahead of them. This plugs the central tube with powder resulting from the crushing 45 of the rear pellets and causes variation in time of explosion of this shell.

I have discovered a certain way in which this can be prevented and by which the accuracy sought by this method of connecting 50 the time fuse with the bursting charge of the shrapnel shell may be fully realized.

My method consists in pressing the powder into a tube to be inserted into the central tube of the shell, in such a way that a

hole is left in the center throughout the en- 55 tire length of the connection.

In this way the powder is so well supported in the tube that it cannot be removed by a pressure greater than that which it must sustain when the shell is fired from 60 the gun.

A preferable way of carrying out the process consists in mixing the solid powder, having a moisture content of about three per cent., with a liquid having no solvent or 65 chemical action upon the powder, and immiscible with water, preferably gasoline or a liquid of similar properties, and tamping the mixture in a thin metal cylinder, thereby not only consolidating the powder but also 70 causing the larger volume of the gasoline to exude, and then drying the powder, at an elevated temperature, in the cylinder to drive off the gasoline and moisture. In the drying operation it might be supposed, from 75 the action of other material under similar conditions, that the powder charge would shrink so that its diameter would be reduced sufficiently to cause it to be readily slipped from the mold. If this would occur, it 80 would produce a unitary charge having some real advantage over the present charge of a number of short pellets, but it would not accomplish the main object of the present invention. As a matter of fact it is found 85 that if any shrinkage occurs, it does not operate to reduce the diameter of the charge, but on the contrary the powder charge, after the drying operation, is found to be so tightly packed within the container as to resist ejec- 90 tion. By utilizing the tubular container with the charge packed therein as a substitute for the string of separately formed pellets, the objects and advantages of my invention are attained.

In carrying out the process for manufacturing my improved charge I utilize preferably an apparatus constructed in accordance with the accompanying drawings, in which—

Figures 1 and 2 represent an elevation, partly in section of the entire apparatus, the upper part of Fig. 2 being a continuation of Fig. 1. Fig. 3 a plan view of the lower and main part of the apparatus. Fig. 4 is a longitudinal sectional view of the finished product.

The explosive powder, together with gaso-

lene, is placed in a tank *a* containing a revoluble stirrer *b*, whereby the powder may be kept in suspension in the gasoline. The amount of gasoline or equivalent liquid added should be sufficient to cover the powder and render the mass capable of flowing. The amount will vary with the particular liquid used and it will also vary with other conditions; but, as an example, it may be stated that with the mixing operation conducted at a temperature of 20° C., equal parts by weight of the powder and gasoline will be found efficient.

After the powder has been stirred into a condition of uniform suspension in the gasoline, the fluid mass is transferred, by means of a centrifugal pump *c*, through a tube *d*, into a vessel *e*. At one end of the vessel *e* is an overflow chamber *f*, spaced from the vessel *e* by a wall *g*, over the top of which the liquid mass overflows so as to maintain constant the level of the vessel *e*. A pipe *h* conducts the overflow back to the mixing tank *a*. Within the vessel *e* is a stirrer *i*, which continuously agitates the mixed powder and gasoline, this being necessary to prevent settlement of the powder, which would otherwise occur quickly.

Arranged along one side of the vessel *e* is a charging chamber *j*. The bottom of the chamber *j* is raised much above the level of the bottom of vessel *e*. In operation, chamber *j* is in open communication with vessel *e*, so that the two form virtually a unitary charging chamber; but a gate *k*, at the conclusion of the mold filling and tamping operation, may be manually applied to separate the vessel *e* from the chamber *j*, thereby shutting off the flow of liquid to the latter.

The bottom of chamber *j* has a series of openings or nozzles *y*, between each of which and a vertically movable holder *m* is confined a tubular container *n*, which is preferably of thin metal. Each holder is threaded 45 in a support *s* secured to the frame of the apparatus.

Extending centrally through each holder *m* and along the axis of the tube *n* is a pin *o*. The upper end of this pin extends through the base of a hollow plunger *p*, which is of a diameter, at its base, adapted to loosely fit the tube *n*. Each plunger *p* extends into a cylinder *r* and carries a piston head *s* which works in the cylinder. Each cylinder has 55 pipe connections *t* and a valve *u* whereby it may be reciprocated hydraulically, pneumatically, or by steam. The cylinders may be connected to one main at the top and to one main at the bottom and one valve will then operate them in unison. Hydraulic actuation presents decided advantages, but it is of the utmost importance that no water should be allowed to reach the powder. Instead of using an ordinary stuffing box, I prefer to provide the piston bushing with

an annular chamber *v* which is connected through a pipe *w* with a vacuum pump, whereby any water that leaks from the cylinder will pass into the chamber *v* and be withdrawn through the pipe *w*.

On the down stroke of the plunger *p* the pin *o*, which is fixed, displaces a certain volume of air. An opening *x* in the wall of the plunger permits this air to escape and affords also an outlet for any liquid that may leak thereinto.

Assume that the tank *a* and vessel *e* are filled, the pump in operation, and the gate *k* positioned to exclude the flow of the mixed powder and gasoline into the charging chamber *j*. The pins *o* have been withdrawn and the holders *m* have been screwed down to allow of the insertion of the tubes *n*. The tubes *n* are now placed in position and the respective holders *m* are screwed up to confine the tubes *n* against the nozzles *y*. The pins *o* are now positioned as shown in the drawings, the plungers *p* are reciprocated, and the gates are removed.

At each uplift of the plungers, a certain amount of the mixture flows into the tubes *n* so as to fill them (say) to about one-sixth of their capacity before the plungers, on their down stroke, enter the tubes and thereby close the mouths thereof. The plungers 95 *s* each descend with sufficient force to tamp the explosive to the desired density, much the larger portion of the gasoline being thereby exuded and forced upwardly out of the tubes *n* between the walls thereof and the plungers. This operation is repeated until the tubes *n* are filled. It will be understood that the plungers are not carried into the tubes *n* a determinate distance, but that the force with which they are depressed is adjusted to give the pressure required to consolidate the powder to the desired degree, the plungers then yielding upwardly. It will also be understood that the plungers operate independently, so that 110 even when operated by the same valve each will exert its own pressure independently of whether or not the amounts of powder in the tubes are exactly the same.

After the tubes *n* are filled, the gate *k* is 115 replaced, the holders *m* lowered, the pins *o* removed, and the tubes *n*, now filled with compacted powder, withdrawn. The powder cylinders 10 are dried at an elevated temperature (say about 110° C.), and the 120 gasoline and moisture that has remained in the powder will be driven off. After the drying operation the powder cylinders are of a density and cohesiveness corresponding to the separate short pellets now in use and 125 remain tightly packed within the shells and cannot be removed therefrom by a pressure exceeding that which it must sustain when the shell is fired from the gun.

While I have described the process as 130

applied to the manufacture of explosive charges for the central tubes of shrapnel shells, it is obvious that the process is applicable to the charging with an explosive 5 of any tube of such great length in proportion to its diameter that instead of acting as a mold from which the charge can be ejected, it acts as a pipe which has been stopped up, and from which no amount of 10 pressure will remove the obstruction, or at least in which the explosive is so tightly pressed that it will not come out under reasonably severe usage. The point where the ratio between the diameter and length 15 of a cylinder changes the conditions from those of a mold from which the charge can be removed to those analogous to a stopped-up pipe cannot be rigidly defined; this factor varying with the character of the explosive. 20 My process may be more definitely distinguished from a mere molding operation by stating that it must be packed into its elongated container by successive pressings, as described, and that only a relatively limited 25 volume of explosive must be consolidated at each pressure; as otherwise the wall of the tube will so effectively support the portion of the charge next to the plunger that the portion farthest away from the plunger 30 will receive little or no pressure. Only by successive pressing actions, therefore, can a charge be built up with the required density, uniformity, hardness and solidity and remain firmly fixed within the tubular container. 35

Having now fully described my invention, what I claim and desire to protect by Letters Patent is:

1. The process of packing an explosive

powder charge tightly within a tubular container, which consists in mixing the powder with a liquid having no solvent or chemical action upon the explosive and successively compressing fractional parts of the mixture to expel a portion of the liquid therefrom 45 and consolidate the powder into a uniform, dense, hard and solid mass held in rigid relationship with the container.

2. The process of packing an explosive powder charge tightly within a tubular container, which consists in maintaining the powder in suspension in a liquid having no solvent or chemical action upon the explosive, flowing into the container a fractional part of the liquid-suspended powder required for a charge, compressing the same, and repeating the powder-admission and compression operations until the container has received a full charge. 50

3. The process of packing an explosive 60 powder charge tightly within a tubular container, which consist in mixing the powder with a sufficient volume of a liquid having no solvent or chemical action upon the powder to enable the same to readily flow, agitating the mixture to maintain the powder in a condition of uniform suspension in the liquid, permitting the mixture to flow into and partially fill the container, tamping the same to compress the powder and expel a 65 portion of the liquid, repeating the filling and tamping operations until the charge is formed, and drying the charge while thus packed in the container.

In testimony of which invention, I have 75 hereunto set my hand, at Philadelphia, Penna., on this 7th day of March, 1918.

FRANCIS I. DU PONT.
